UNITED STATES PATENT OFFICE.

ROBERT E. PEICKERT, OF DUMONT, MINNESOTA.

PENHOLDER.

No. 884,849.

Specification of Letters Patent.

Patented April 14, 1908.

Application filed June 27, 1907. Serial No. 381,098.

To all whom it may concern:

Be it known that I, ROBERT E. PEICKERT, citizen of the United States, residing at Dumont, in the county of Traverse and State of Minnesota, have invented certain new and useful Improvements in Penholders, of which the following is a specification.

This invention has relation to penholders generally and particularly to that class that are designed to release the penpoint when desired without taking hold of it or manipulating it in a way that will occasion the soiling of the fingers or hands.

It is the purpose of this invention to provide improvements that will simplify the construction and enhance the efficiency of the penholder and render it capable of production by a process and means that will reduce its cost to a minimum.

20 The nature of the invention is ascertainable from the device portrayed in the annexed drawings forming a part of this specification and in view of which the improvements will first be described with respect to 25 its construction and mode of operation and use, and then be pointed out with particularity in the subjoined claim.

Of the drawings: Figure 1 is a plan of the invention. Fig. 2 is a longitudinal section. 30 Fig. 3 is a like view showing a slight modification.

The same character of references indicate the same parts or features, as the case may be wherever they occur.

35 In the drawings, 4, designates the penstock which may be of wood or any other suitable material, and which is reduced at its forward end to receive thereover the inner end portion of a sleeve 5, of thin metal having an opening B therein.

A designates a strip of resilient metal having its inner end formed as a straight shank, 6, that is extended in a groove formed in the lower side of the reduced portion of the penstock between the latter and the sleeve 5. Just forward of the end of the penstock the said resilient strip is doubled upon itself, and said doubled portion is bent upward in a plane at a right angle to the plane of the penstock, and extended through the opening B in the top of the sleeve. The upper end of the said doubled portion of the strip is crushed down or flattened to form a head, 7, that stands a slight distance above the sleeve 5. The doubled portion of the strip below the head forms a shank, 8, that ex-

tends a short distance into the sleeve. From the lower end of the shank 8 the resilient strip is bent upward to the upper inner side of the sleeve and then extends outward in the plane of the sleeve to near its end, as at 9, whence a recurvate bend 10, is given to its end portion, which bend is of such form that the terminal 11 will bear on the bottom of the interior of the sleeve.

Under the construction described, the shank 12 of the penpoint 13 may readily be inserted between the outer end of the sleeve and the portion 9 of the resilient strip, and be there held with all requisite rigidity and firmness to practice writing as is common with any pen and penholder. Instead of the end portion 9 of the strip being given a recurvate bend 10, as shown in Fig. 3 it may be continued in a straight line to near the outer end of the sleeve, the terminal being bent down, as at 14, just sufficiently to allow the shank 12 of the penpoint to be forced into place, as shown in Fig. 3.

In use the head 7 will afford a convenient grip for the fingers on the penstock to keep it from turning while in the act of writing, without any tendency to depress the same; and when it is desired to release the pen from the holder, by pressing down on the head 7, the portion 9 of the strip A, acting as a stiff spring, will be depressed, releasing the shank 12 of the penpoint which will drop away without touching it with the fingers.

What is claimed is:

A penpoint-releasing penholder comprising a penstock, a cylindrical sleeve on the forward end of the penstock having a hole in its upper side, a resilient strip of metal having its inner portion formed as a shank engaged between the penstock and the portion of the sleeve surrounding the same, the intermediate portion doubled upon itself forming a shank extended through the hole in the sleeve, the outer part of the doubled portion being flattened to form a head, and the forward portion of said strip being extended outward in the plane of the upper inner side of the sleeve to receive and hold the shank of the penpoint.

In testimony whereof I have affixed my signature, in presence of two witnesses.

ROBERT E. PEICKERT.
